UNITED STATES PATENT OFFICE

2,570,186

MACHINE FOR OPENING CLOSURE MEMBERS HAVING CRIMPED FLANGES

August E. Almgren, Hillside, N. J., assignor to
American Can Company, a corporation of New Jersey

Application February 8, 1950, Serial No. 143,026

8 Claims. (Cl. 226—129)

1

The present invention relates to a machine for opening or loosening closure members or containers and has particular reference to devices for prying loose and lifting closure members the flanges of which are crimped over a projecting ledge of the containers. This is an improvement on the opening devices included in the machine disclosed in United States Patent 2,284,660 issued June 2, 1942 to John M. Hothersall and August E. Almgren on Container Treating Machine.

In the manufacture of fibre containers for milk and certain other liquid products, considerable care is taken to maintain the containers in a sterile condition. Toward this end the completed containers before shipment to the dairy for filling, are sterilized and their closure members closed and sealed to protect the interior of the containers against contamination during shipment and handling. To insure against inadvertent opening of the closure members during shipment and handling of the containers, the protecting lips or flanges of the closure members are crimped under the projecting ledge of the containers. This crimped lip or flange causes some difficulty in opening the closure members immediately prior to filling the containers at the dairy.

The instant invention contemplates overcoming this difficulty by the provision of devices for prying the lip loose and for lifting the closure members.

An object of the invention is the provision of devices for opening closure members having lips crimped under a ledge of a container, wherein the crimped-under lips of the closure members may be readily loosened or pulled out and utilized in opening the closure members without distortion or damage of the lips so that the lips may be used to subsequently reseal the containers after filling or other treatment.

Another object is the provision of such devices wherein the decrimping or unsealing of the lips and the lifting of the closure members is effected by mechanical fingers without the use of vacuum cups which are now extensively utilized for such a closure member opening operation.

Another object is the provision of such devices which are adapted to automatic high-speed machines through which the containers may pass in a continuous procession.

Numerous other objects and advantages of the invention will be apparent as it is better understood from the following description, which, taken in connection with the accompanying drawings, discloses a preferred embodiment thereof.

Referring to the drawings:

2

Figure 1 is a top plan view of a container opening mechanism embodying the present invention, with parts broken away;

Fig. 2 is a front elevation of a portion of the mechanism shown in Fig. 1, with parts broken away;

Fig. 3 is a side elevation of the parts shown in Fig. 2, with parts broken away;

Figs. 4, 5, 6, 7 and 8 are enlarged fragmentary 10 details showing the steps of opening a container; and

Fig. 9 is an enlarged perspective view of one of the container opening fingers used in the mechanism.

15 As a preferred or exemplary embodiment of the invention the drawings illustrate principal parts of a container treating machine of the character disclosed in the above mentioned Hothersall et al. Patent 2,284,660 and includes an

20 improved container opening mechanism for re-opening sterile closed empty fibre milk containers A preliminary and as an incident to filling the containers with milk. The container A illustrated in the drawings is similar to that disclosed in 25 United States Patent 2,085,979 issued July 6, 1937 to John M. Hothersall on Container. This container comprises a rectangular shaped body B (Fig. 3) having its upper end formed with an inwardly extending tapered bead or neck C terminating in an outwardly projecting flange which 30 envelopes a marginal portion of a flat top member or disc E (Fig. 1) forming with the latter a projecting ledge D.

The top member E is formed, in one corner 35 thereof, with a filling and dispensing opening F (Fig. 1) which is sealed by a friction plug closure member G preferably hingedly secured by a wire staple H to the container top member E. The closure member G is formed with an outer lip or flange J which extends over the ledge D of

40 the container along portions of two adjacent and converging sides thereof and which preferably is bent inwardly or crimped under the ledge D during the manufacture of the container to maintain the closure member G in a closed position during 45 shipment and storage to insure against contamination of the sterile interior of the container.

The closure member G remains in this closed position from the time the container is finished at 50 the factory until immediately prior to the filling of the container at the dairy, at which time the crimped-under lip J is pulled loose and the closure member is hinged open to gain access to the interior of the container. It is to this pulling loose

55 or unsealing of the crimped-in lip J and the open-

ing of the closure member G that the instant invention is particularly directed.

As disclosed in the above mentioned Hothersall et al. Patent 2,284,660, the containers to be opened are arranged in an upright position supported on a table 11 (Fig. 1) and are advanced preferably along a curved path of travel in spaced and timed order by an intermittently rotated horizontal turret 12 having peripheral pockets 13 in which the containers are located with the corners of the containers adjacent the closure members G extending outwardly as shown in Fig. 1.

The container opening mechanism is located adjacent the curved path of travel of the containers at an opening station K where the containers come to rest during their intermittent advancement. This mechanism includes a curved rack 15 (Figs. 2 and 3) disposed in a vertical plane and located above and transversely of the path of travel of the containers A. The sides of the rack 15 are formed with laterally projecting tongues 16 which slide in a curved guideway 17 as shown in the Hothersall et al. Patent 2,284,660. This guideway is formed in a bracket 18 secured to a frame 19 which may be the main frame of the treating machine.

The curved rack 15 is actuated by a spur gear 21 which is keyed to a short shaft 22 carried in a pair of spaced bearings 23 formed in the bracket 18. The shaft 22 also carries a pinion 25 which meshes with a straight actuating rack 26 slidably retained in a groove 27 formed in the bracket 18. The straight rack 26 preferably is connected by a link 28 to any suitable source of reciprocating motion, such as the lever and cam means disclosed in the above mentioned Hothersall et al. Patent 2,284,660 for reciprocating the rack in time with the advancement of the containers A into and out of the opening station K. Through this reciprocating motion the curved rack 15 slides in its guideway 17 into and out of operating position relative to a container A at rest at the station K to effect the opening of the closure member G.

Opening or loosening of the closure member G is effected preferably by a pair of opening fingers 31 (Figs. 2, 3, 5, 8 and 9) which are movable with the curved rack 15 through parallel vertical planes extending transversely of the path of travel of the containers A and disposed adjacent the outer corner of the container at rest at the opening station K. The two fingers 31 are disposed at right angles to each other or substantially so, in order that in the initial opening position of the fingers they will be in vertical planes located substantially normal to the sides of the container adjacent its outer corner.

For this purpose the opening fingers 31 intermediate their ends, are mounted on pivot pins 32 (Figs. 2, 3, 5 and 8) carried in pairs of lugs 33 which project from an opening head 34 preferably formed as a lateral extension of the curved rack 15. The inner ends of the fingers terminate in a relatively thin flat nose or jaw 35 (see Fig. 9) which taken with a finger 31 constitute a movable jaw.

Adjacent these nose portions 35 of the fingers 31, the head 34 is formed with a pair of fixed jaw faces or jaws 36 which co-operate with the pair of movable jaws in opening the container. Adjacent the fixed jaws 36, the head 34 carries a clamping pad 37 (Figs. 5 and 8) which is located in such a manner as to clamp against the top of the closure member G of a container A at the

opening station K when the opening head 34 is in its initial opening position.

The clamping pad 37 is formed with a stem 38 which extends through the head 34. A cap 39 on the outer end of the stem restrains the pad against displacement from the head, while a compression spring 41 interposed between the head and the pad provides for yieldable action of the pad. The spring is coiled around the stem 38.

The outer ends of the two opening fingers 31 are formed with angularly disposed tail members 45 (Figs. 5 and 9). These tail members 45 are yieldably held against the inner ends of a pair of finger actuating pins 46, by compression springs 47 which press against the inner ends of the fingers. The springs are housed in sockets 48 formed in the head 34. These springs keep the jaws 35, 36 open.

The finger actuating pins 46 are slideably disposed in bores 51 formed in the head 34 at an angle substantially radial with respect to the curved rack 15. The outer ends of the finger actuating pins 46 operate against a pair of spaced and parallel stationary cam rails 52 which are formed integrally with the bracket 18. These cam rails are curved and are disposed adjacent and concentric with the path of travel of the curved rack 15. Compression springs 53 coiled around the finger actuating pins 46 press the pins against the cam rails 52. These springs are interposed between a collar 54 formed on each of the pins and a bushing 55 threaded into the head 34 for each pin.

When a container A moves into the opening station K, the curved rack 15 and its attached opening head 34 are in a position at the right as viewed in Fig. 3 where the head 34 is above and clear of the container so as to prevent interference with the advancement of the container. As soon as the container is at rest at this station, the curved rack 15 through actuation of the straight rack 26, pinion 25 and gear 21, moves toward the left as viewed in Fig. 3 and carries the head 34 over the top of the positioned container and downwardly toward the outer corner of the container to the position illustrated in Fig. 3.

During this travel of the head 34, the outer ends of the finger actuating pins 46 ride along a high portion 56 of the cam rails 52. These high portions of the cams press the pins inwardly against the tail members 45 of the fingers 31 and thus keep the jaws 35 of the fingers against the fixed jaws 36 of the head as best shown in Fig. 4. As the head 34 approaches its lowermost position as shown in Fig. 3, the clamping pad 37 engages against the closure member G of the container and holds it firm under the pressure of the pad spring 41. The head continues to lower just a trifle and this brings the head to its initial opening position as shown in Figs. 3 and 5.

As the head moves into its initial opening position as mentioned above, the finger actuating pins 46 ride off the high portions 56 of the cam rails 52 as best shown in Fig. 5 and are thereby released or freed so that their compression springs 53 slide them outwardly. This releases the pressure on the tail members 45 of the fingers 31 and permits the springs 47 to force the movable jaws 35 of the fingers away from the fixed jaws 36. This forces the movable jaws 35 against the lips or flanges J of the closure member G as shown in Fig. 4 and causes the outer edges of the mov-

able jaws to snap past and engage under the lips or flanges as shown in Figs. 4 and 5.

With the movable jaws 35 in this position, engaged under the lips or flanges J, the curved rack 15 starts to move back through a return stroke to its original position. As soon as the rack begins to move, the finger actuating pins 46 ride up onto the high portions 56 of the cam tracks 52 and this action forces the pins inwardly against the tail members 45 of the fingers 31 and thus closes the movable jaws 35. This closing of the movable jaws 35 prys the lips or flanges J outwardly away from their crimped-in position under the ledge D of the container and clamps the pried-out lips or flanges against the fixed jaws 36 of the head 34 as best shown in Fig. 6. It will be noted that this action bends the lips or flanges outwardly away from the container to an angle of substantially forty-five degrees.

As the rack 15 and its attached head 34 continue to move up through their return stroke, the movable jaws 35 continue to hold the lips or flanges J clamped against the fixed jaws 36 and thus raise the closure member G as shown in Fig. 7. This lifting action continues as the head moves up, until the closure member G is in its fully open position as shown in Fig. 8. When the closure member G is in this fully opened position, the finger actuating pins 46 ride off the high portion 56 of the cam rails 52 and are again released to permit opening of the movable jaws 35 in respect to the fixed jaws 36 and this releases the lips or flanges J from the head 34. The head remains in this position for a subsequent container and thus the released movable fingers 35 remain in position and act as a stop to prevent reclosing of the closure member. This completes the opening operation.

Upon the next advancement of the opened container A by the turret 12, the opened closure member G moves laterally away from the opening fingers 31 and is engaged behind a stationary holding rail 57 (Fig. 1). This rail retains the closure member G in its opened position as the container advances for subsequent treatment.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a machine for opening closure members having a portion crimped over a projecting ledge of a container, the combination of clamping means operable against a top portion of the closure member of a container and having an edge extending substantially to the projecting ledge of the container for holding said member in closed position, and a finger having a jaw insertable under the crimped portion of the closure member and movable away from the container for prying said crimped portion loose from the container to facilitate opening of said closure member, said crimped portion, during said prying operation, being limited by said clamping means to bending outwardly substantially along said edge of the clamping means.

2. In a machine for opening closure members having a portion crimped over a projecting ledge of a container, the combination of a head member movable toward a container to be opened, clamping means carried in said head member and operable against a top portion of the closure member of the container and having an edge extending substantially to the projecting ledge of the container for holding said closure member in closed position, and a finger carried in said head member and insertable under the crimped portion of the closure member and movable away from the container for prying said crimped portion loose from the container to facilitate opening of said closure member, said crimped portion, during said prying operation, being limited by said clamping means to bending outwardly substantially along said edge of the clamping means.
3. In a machine for opening closure members having a portion crimped over a projecting ledge of a container, the combination of a finger having a jaw insertable under the crimped portion of the closure member of a container and movable away from said container for prying said crimped portion loose from the container to facilitate opening of said closure member, a second jaw disposed adjacent said finger jaw, means for closing said jaws with the pried loose crimped portion interposed between them for firmly gripping said crimped portion, and means for shifting said closed jaws for opening said closure member through the grip on said crimped portion.
4. In a machine for opening closure members having a portion crimped over a projecting ledge of a container, the combination of a pair of co-operating jaws, one of said jaws being engageable under the crimped portion of the closure member of a container for prying said crimped portion loose from the container and for clamping said portion against the other of said jaws, and means for moving said closed jaws and the crimped portion of the closure member clamped therebetween in unison for shifting said closure member into an open position relative to said container.
5. In a machine for opening closure members having a portion crimped over a projecting ledge of a container, the combination of a fixed jaw movable into position adjacent the crimped portion of the closure member of a container, a movable jaw disposed adjacent said fixed jaw, spring means between said jaws for holding them open for engagement of said movable jaw under said crimped portion of the closure member, jaw actuating means operative against said movable jaw for pulling said crimped portion of the closure member loose from said container and for clamping it tightly between said jaws, and means for moving said closed jaws and the crimped portion of the closure member clamped therebetween for shifting said closure member into an open position relative to said container.
6. In a machine for opening closure members having a portion crimped over a projecting ledge of a container, the combination of a head movable along a predetermined path of travel into position adjacent the crimped portion of the closure member of a container, a fixed jaw formed integrally with said head, a movable jaw pivotally mounted in said head adjacent said fixed jaw and engageable under the crimped portion of the closure member on said container, a jaw actuating pin carried in said head and operable

against said movable jaw, stationary means disposed adjacent the path of travel of said head and engageable with said pin for closing said movable jaw for pulling said crimped portion of the closure member loose from said container and for clamping it tightly between said closed jaws, and means for moving said head and the closed jaws for shifting said closure member into an open position relative to said container.

7. In a machine for opening closure members having a portion crimped over a projecting ledge of a container, the combination of a curved rack movable along a curved path of travel adjacent the closure member of a container to be opened, a head carried on said rack and movable by said rack into a position adjacent the crimped portion of said closure member, a fixed jaw formed integrally with said head, a movable jaw pivotally mounted in said head adjacent said fixed jaw and engageable under the crimped portion of the closure member on said container, a jaw actuating pin carried in said head and operable against said movable jaw, stationary cam means disposed adjacent the path of travel of said head and engageable with said pin for closing said movable jaw for pulling said crimped portion of the closure member loose from said container and for clamping it tightly between said closed jaws, means for moving said rack and its attached head and the closed jaws for shifting said closure member into an open position relative to said container, and means included in said cam means for releasing said actuating pin to open said jaws for freeing the opened closure member from said jaws.

8. In a machine for opening closure members having a portion crimped over a projecting ledge of a container, the combination of a head movable along a path of travel adjacent the closure member of a container to be opened and into a position adjacent the crimped portion of said closure member, a pair of fixed jaws formed integrally with said head and disposed at an angle to each other for positioning adjacent two adjoining sides of said container, a pair of movable jaws mounted in said head and disposed one adjacent each of said fixed jaws for engagement under the crimped portion of the closure member on said container, jaw actuating means operative against said movable jaws for pulling said crimped portion of the closure member loose from said container and for clamping it tightly against said fixed jaws, and means for moving said head and its closed jaws with the crimped portion of the closure member interposed between the jaws for shifting the closure member into an open position relative to said container.
